To all whom it may concern:

Be it known that I, Martin Glaberson, a citizen of the United States, residing at Ardsley, in the county of Westchester and State of New York, have invented a new, original, and ornamental Design for a Safety Razor, of which the following is a specification; reference being had to the accompanying drawing forming a part hereof.

In the drawing:

Fig. 1 is a front elevational view of a safety razor, showing my new design;

Fig. 2 is a rear elevational view of the safety razor shown in Fig. 1; and

Fig. 3 is a side elevational view of the same.

The essential features of my design reside in the portions shown in solid lines on the drawing.

I claim:

The ornamental design for a safety razor, substantially as shown and described.
